CLAIM

The ornamental design for a binder with zip, as shown and described.

DESCRIPTION

FIG. 1 is a front, left and top perspective view of a binder with zip, showing my new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines showing stitching in the figures forms no part of the claimed design. The broken lines on the rear of the article in FIG. 3 depict portions of the binder with zip that form no part of the claimed design.

1 Claim, 7 Drawing Sheets
